UNITED STATES PATENT OFFICE.

THOMAS G. WILLSON, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

APPARATUS FOR GOVERNING THE PASSAGE OF CARS OR VEHICLES ALONG A RAILWAY AND THE CONTROL THEREOF.

1,259,184.

Specification of Letters Patent.

Patented Mar. 12, 1918.

Application filed July 20, 1916. Serial No. 110,377.

To all whom it may concern:

Be it known that I, THOMAS G. WILLSON, a citizen of the United States, residing at Swissvale, in the county of Allegheny and State of Pennsylvania, have invented certain new and useful Improvements in Apparatus for Governing the Passage of Cars or Vehicles Along a Railway and the Control Thereof, of which the following is a specification.

My invention relates to machines for the control of railway traffic governing apparatus, and more particularly to machines of this character comprising levers for the mechanical control of such apparatus and other levers controlled by the said apparatus for governing the first-mentioned levers.

I will describe one form of controlling machine embodying my invention and then point out the novel features thereof in claims.

In the accompanying drawings, Figure 1 is a vertical sectional view of a controlling machine embodying my invention. Fig. 2 is a sectional view on line II-II of Fig. 1 looking in the direction of the arrows. Fig. 3 is a sectional view on line III-III of Fig. 1 looking in the direction of the arrows. Fig. 4 is a view showing in front elevation the arrangement of the locking parts on shaft 2 and slide bar 16 when levers E and M of Fig. 1 are in their normal positions. Fig. 5 is a view similar to Fig. 4, but showing these locking parts in the positions which they occupy when lever E is in the intermediate position and lever M is unlatched. Fig. 6 is a view similar to Fig. 4, but showing the locking parts in the positions which they occupy when both levers E and M are reversed. Figs. 4^a, 5^a and 6^a are views showing in side elevations the locking parts shown in Figs. 4, 5 and 6 in the positions which they occupy in the latter views respectively. Fig. 7 is a diagrammatic view of one arrangement of apparatus and circuits for the control of a railway switch by levers E and M.

Similar reference characters refer to similar parts in each of the views.

Referring first to Fig. 1, M designates a mechanical lever mounted to oscillate on a pin s in a supporting frame A, which lever, as I shall describe hereinafter, is adapted to

operate by a rod 10 certain railway traffic control apparatus, as for instance, a railway switch. Lever M has two extreme positions, a normal position which is the position wherein the lever is shown on the drawing, and a reverse position indicated by a dotted line designated r. The lever may be locked in one or the other of these positions by a block 11 coacting with the extremities of a stationary member 12, usually termed "quadrant", because the surface of this member (on which surface block 11 rides during a movement of lever M) is the arc of a circle whose center is at pin s. The block 11 is raised from the locking position or lowered to said position by a latch handle 13 on lever M. The up-and-down movements of this block control a rocker link 14 having a slot 13^a in which block 11 slides during movements of lever M. For a movement of this lever from "normal" to "reverse" the link 14 is first rocked counterclockwise by the unlatching of the lever, then remains stationary during the reversal of the lever, and is rocked counterclockwise again when the lever is locked in its reverse position. For a lever movement in the opposite direction link 14 is rocked clockwise in similar manner. These movements of the link 14 are communicated to a slide bar 16 which at its lower end is pin-connected to link 14 and which at its upper end is free to slide in a bearing 17 fixed to the frame of the machine. The up-and-down movements of this bar caused by the latching and unlatching of lever M are controlled in a manner which I shall describe presently.

In the upper part of the machine frame A is mounted an indication lever E, which has three positions, namely, a normal position (in which position the lever is shown on the drawing), an intermediate position designated i, and a reversed position designated r. Lever E operates through bevel gearing e a horizontal shaft 1, which is controlled by indication magnets R and N as I shall explain hereinafter. Shaft 1 is operatively connected with a horizontal shaft 2, through an adjustable rod 3, which, as best shown in Fig. 2, is fixed at its upper end to an arm 4 on shaft 1, and at its lower end to an arm 5 on shaft 2. When lever E is moved

from the normal to the intermediate position, shaft 1 is turned through an angle of 30° in counterclockwise direction as viewed in Fig. 2, and shaft 2 is turned through the 5 same angle in clockwise direction. A further movement of lever E, *i. e.*, from the intermediate to the reverse position, causes shafts 1 and 2 to turn in the above-mentioned directions through another 30 degrees.

The shaft 2 controls the movements of the slide bar 16 by means of a segment 18 affixed to the end of the shaft as I shall now explain with reference particularly to Figs. 15 4, 5, 6 and 4^A, 5^A, 6^A. Segment 18 is provided with two dogs, 19 and 20, which are adapted to coact with a tongue 21 riveted to slide bar 16. In Figs. 4 and 4^A I have shown shaft 2 and slide bar 16 in positions 20 corresponding to the normal positions of levers E and M, in which positions tongue 21 abuts against the under surface of dog 19, thus preventing an upward movement of the slide bar 16 and, consequently, an unlatching 25 of lever M. When lever E is operated to its intermediate position shaft 2 rotates segment 18 counterclockwise through 30 degrees, so that dog 20 engages the left side of tongue 21, preventing a movement 30 of the lever E past the intermediate position. Lever M is now free to be unlatched because slide bar 16 can be raised, tongue 21 slipping between dogs 19 and 20, as shown 35 in Figs. 5 and 5^A, so that shaft 2 is firmly locked against rotation and lever E is prevented from movement in either direction from its intermediate position. Tongue 21 remains in the position shown in Fig. 5 while lever M is being reversed to operate 40 the corresponding traffic control device. When lever M is latched in the reversed position bar 16 is raised until dog 20 is free to pass under tongue 21, so that shaft 2 can be turned in the counterclockwise direction. 45 Lever E may therefore be turned to its reverse position, so that segment 18 moves into the position shown in Figs. 6 and 6^A, in which position the dog 20 slips under tongue 21 and prevents a downward movement of 50 slide bar 16, thus locking the lever M in the reverse position. The operation of the locking parts for an operation of the levers E and M from "reverse" to "normal" is similar and need not be described in detail. 55 Thus it appears that the mechanical lever can be operated from one position to the other only by a corresponding movement of the indication lever, and it is impossible to have simultaneously a normal position of 60 one lever and a reverse position of the other.

In Fig. 7 I have indicated the above-mentioned control of the levers E and M by a dotted line between the pivotal points of the levers. Lever M operates through rod 65 10 a sliding plate 23 which is connected by

a rod 26 to a sliding contact member 27 which coacts with two pairs of stationary contact springs 28 and 29, so located that member 27 bridges a pair of springs at each end of the stroke of lever M. Plate 23 is 70 provided with a cam slot 24 for receiving a roller 25 mounted on the operating rod 50 of a switch S. The shape of the cam slot 24 is such that a reversal of lever M operates the switch S from its normal to its 75 reverse position only after an initial movement of plate 23 sufficient to open contact 29, and contact 28 is closed only after the reversal of switch S is completed. Similarly, an operation of lever M from its reverse to its normal position causes consecutively, the opening of contact 28, the movement of switch S to its normal position, and the closure of contact 29.

The movements of lever E are controlled 80 by the indication magnets R and N hereinbefore mentioned. These magnets operate latches 30^a and 30^b which, as well understood in the art, coact with segments 31^a and 31^b on shaft 1, in such manner that for 90 a movement of lever E from normal to reverse, the lever is arrested in the intermediate position until magnet R is energized, whereas for a movement in the opposite direction the lever is arrested in the 95 intermediate position until magnet N is energized. Lever E further operates a contact finger 35 to engage a contact plate 37 when the lever reaches its reverse position, and to engage a contact plate 36 when the 100 lever passes into the normal position.

The circuits for magnets R and N are controlled by the contacts 28 and 29 hereinbefore mentioned and by the contact finger 35. The circuit for magnet R is as follows: from battery 38, through wire 39, contact 35—36, wire 40, magnet R, wire 41, contact 28, wire 42 to battery 38. Magnet R can therefore be energized only when switch S is in the reversed position. Similarly, the 105 circuit for magnet N is as follows: from battery 38, through wire 39, contact 35—37, wire 43, magnet N, wire 44, contact 29 and wire 42 to battery 38, so that magnet N can be energized only when the switch S is normal. 110

The operation of the apparatus is as follows:

To move the switch S from the normal 120 position shown on the drawing to the reverse position, the operator throws lever E to the intermediate position, in which position further movement of lever E is prevented by the co-operation of latch 30^a and segment 31^a, and also by the mechanical 125 locking between levers E and M, as hereinbefore explained. This movement of lever E releases lever M and the operator reverses this lever, causing a reversal of switch S and a closure of switch contact 28. Closure 130

of this contact brings about the energization of magnet R and the consequent raising of latch 30^a for releasing lever E. The operator throws lever E to the reverse position 5 to lock lever M reversed, as hereinbefore explained. During the last-mentioned stroke of lever E finger 35 is operated from engagement with contact plate 36 into contact with plate 37, thus opening the circuit of 10 magnet R and dropping latch 30^a. The operation of the apparatus for a reverse movement of the switch is similar and need therefore not be described.

As is well known in the art, an interlocking machine usually comprises a plurality of levers, similar to levers E and M, which levers are interlocked by means of locking bars comprised in a locking bed. As shown 15 in Figs. 1 and 3, shaft 2 operates a locking bar 7 through a crank arm 8 in such manner that angular movements of shaft 2 cause longitudinal movements of bar 7. The movements of bar 7 effect the desired locking in a manner well understood in the art. 20 It will be seen from the foregoing that by virtue of my invention I am enabled to convert a standard Saxby and Farmer mechanical interlocking machine into an electro-mechanical machine by merely replacing 25 the direct connection between the latch link 14 and the shaft 2 by the interlocking means shown in Fig. 4, and adding the superstructure carrying the indication levers 1.

Copies of this patent may be obtained for five cents each, by addressing the "Commissioner of Patents, Washington, D. C."

Although I have herein shown and described only one form of apparatus embodying my invention, it is understood that various changes and modifications may be made therein within the scope of the appended claims without departing from the 35 spirit and scope of my invention.

Having thus described my invention, what I claim is:

Interlocked controlling apparatus for railway traffic governing devices, comprising 45 a Saxby and Farmer mechanical interlocking machine having the usual mechanical levers, latches for said levers, transverse shafts one for each latch, and the usual interlocking bed having longitudinally movable bars operated by said shafts; a superstructure on said machine carrying a plurality of indication levers each of which is operatively connected with one of said transverse shafts; and means interposed between each latch and the corresponding transverse shaft for preventing release of the latch when the corresponding indication lever is in extreme position and for preventing movement of such indication lever when 50 such latch is released.

In testimony whereof I affix my signature in presence of two witnesses.

THOMAS G. WILLSON.
